Inventor

Henry H. Brandes

C. Snow & Co.

UNITED STATES PATENT OFFICE.

HENRY H. BRANDES, OF CORYDON, KENTUCKY, ASSIGNOR OF ONE-HALF TO
JAMES F. SULLINGER, OF SAME PLACE.

WHIFFLETREE.

SPECIFICATION forming part of Letters Patent No. 417,224, dated December 17, 1889.

Application filed September 10, 1889. Serial No. 323,530. (No model.)

To all whom it may concern:

Be it known that I, HENRY H. BRANDES, a citizen of the United States, residing at Corydon, in the county of Henderson and State of Kentucky, have invented a new and useful Whiffletree, of which the following is a specification.

The invention relates to whiffletrees.

The object of the present invention is to provide a whiffletree of simple and inexpensive construction adapted to be attached to vehicles to enable an animal to start with a light or heavy load or an empty vehicle without experiencing any sudden strain, and to prevent the jars to animals incident to passing over rough surfaces.

The invention consists in the construction and novel combination and arrangement of parts hereinafter fully described, illustrated in the accompanying drawings, and pointed out in the claims hereto appended.

In the drawings, Figure 1 is a perspective view of a whiffletree constructed in accordance with this invention. Fig. 2 is a detail view of the plate that carries the conical spring and rubber buffer. Fig. 3 is a longitudinal sectional view of the whiffletree.

Referring to the accompanying drawings by letter, A designates a whiffletree of ordinary construction, which is provided on its rear face with a flat spring B, which is attached thereto intermediate of its ends by a metal band C, that passes around the whiffletree and the spring and is provided with a perforation c', which also extends through the whiffletree and receives the pin that couples the same to a tongue, a doubletree, or the cross-bar of a pair of shafts. The ends b of the flat spring are bent back upon themselves and around pins or bolts D, which pass through perforations in the side of draft-clips E. When a load is started, the spring B will give and will enable the strain to be slowly communicated to the animal to prevent any sudden jars; and in order to enable this result to be produced should the load be light or heavy, the conical spiral springs F are interposed between the ends of the flat spring and the whiffletree. The conical springs are secured to plates f, which are attached to the rear face

of the whiffletree, the springs being secured to said plates before the attachment of the latter to the whiffletree. The plates are provided at their outer ends with small projections f', which prevent the sides of the draft-clip, which are arranged upon the top and bottom of the whiffletree, from swinging out beyond the ends of the latter.

Conical rubber buffers G are secured to the said plate f within the conical spiral spring- rods F, and when the vehicle is passing over rough and uneven ground they receive the jars incident to such passage and prevent any sudden strains upon the horse.

In order to regulate the pressure of the springs, a series of registering perforations d are provided in the sides of the clip E, which enable the pin to be adjusted nearer or farther from the conical spring F and the whiffletree.

The whiffletree is provided with hooks H, to which are connected the stay-chains, and the clips which secure the hooks in place also serve to fasten the inner end of the plate f, to which the conical springs and buffers are attached.

From the foregoing description and the accompanying drawings the construction, operation, and advantages of the invention will readily be understood.

Having thus described my invention, what I claim is—

1. The combination of the whiffletree, the spring B, secured thereto intermediate of its ends, the draft-clips attached to the end of the spring B, the plates F, provided with projections f' at their outer ends to prevent the draft-clip swinging out beyond the ends of the whiffletree, the conical spiral springs secured to the plates f and interposed between the whiffletree and the ends of the spring B, and the conical buffers arranged within the springs, substantially as described.

2. The combination of the whiffletree, the flat spring secured thereto, the draft-clips provided with a series of perforations, the bolts D, securing the ends of the spring B to the clips, and the conical spiral springs interposed between the whiffletree and the ends of the spring B, substantially as described.

3. The combination of the whiffletree, the

spring B, secured intermediate of its ends to said whiffletree, the draft-clips attached to the end of the spring, and the rubber buffers arranged within the springs, substantially as described.

4. The combination of the whiffletree, the spring secured thereto intermediate of its ends, the draft-clips attached to the end of the spring, and the conical rubber buffers interposed between the whiffletree and the spring, substantially as specified.

5. The combination of the whiffletree, the spring B, attached to the rear thereof, the

draft-clips secured to the ends of the spring, the conical spiral springs interposed between the ends of the spring B and the whiffletree, and the conical buffers arranged within the conical spring, substantially as described.

In testimony that I claim the foregoing as my own I have hereto affixed my signature in presence of two witnesses.

HENRY H. BRANDES.
